GLOW DISCHARGE STABILIZER TUBE

Erwin Müller, Berlin-Eichwalde, Germany, assignor to Stabilovolt G. m. b. H., Berlin, Germany, a company

Application November 12, 1938, Serial No. 240,133
In Germany November 11, 1937

4 Claims. (Cl. 250—27.5)

(Granted under the provisions of sec. 14, act of
March 2, 1927; 357 O. G. 5)

The present invention relates in general to glow discharge tubes for regulating the voltage of electric current, and has reference in particular to glow discharge potential dividers provided with wall electrodes.

According to the present invention, discharges of relatively strong currents, between 1 and 100 ma. or more, have to start from these wall electrodes which—to give an example—may be the only electrodes in the discharge vessel. This result is produced by the means herein after described.

In the drawing, several tubes according to my invention are shown by way of example.

Fig. 1 is a longitudinal sectional view of one form of construction of the tube according to the invention.

Fig. 2 is a longitudinal sectional view showing a modified form of construction of the new tube.

Fig. 3 is a longitudinal sectional view and shows a further modification of the invention.

Fig. 4 is likewise a longitudinal sectional view illustrating another form of construction.

Fig. 5 is a longitudinal sectional view of a still further modification, and

Fig. 6 is a transverse sectional view on line 5—5 of Fig. 5.

In the embodiment shown in Fig. 1, 1 represents the cathode layer, 2 denotes the bulb and reference numeral 3 denotes anode layer. Lead-in wires 5 and 6 serve to connect the cathode and anode, respectively, with the terminals of an outside current source. The lead-in wires 5 and 6 extend through the inner glass projection 4.

The wall electrodes may consist of fire-melted layers of precious metals, or they may be metal films produced by evaporation in high-vacuum or by cathode atomization in the gas-filled atmosphere, or they may consist of a coating applied by spraying or a chemical deposit, preferably of a thin layer of graphite (Aquadag). The electrodes may be made active by known processes, for example by the use of metals of the alkaline earths or their alloys, or by means of atomized magnesium. In the case of graphite electrodes, especially colloidal graphite deposits (Aquadag) can be used as activating medium. In such a case, the high reduction properties of carbon prevents decomposition of alkaline earth alloys, which easily decompose when exposed to air at high temperatures, from becoming inactivated. The graphite may also have additions of other electrically conductive materials or easily reducing metal oxides, or alternatively, easily reducing metal oxides can be applied to the walls

of the tubes by means of a binder which, in the forming process, during manufacture, would be adsorbed to the metals by hydrogen.

The manufacture of the glow discharge potential divider tubes is considerably simplified and made more economical by the use of wall electrodes, especially in view of the simplicity of the application of the coatings. In spite of the small space requirements, cooling through the walls is much more effective than in the case of electrodes which are free standing in the interior of the tube. On the other hand, the low heat conductivity of a glass bulb, for instance, brings about but negligible heating of the electrode material which is rendered active when the stem is inserted into the bulb. Thus, the activating material is prevented from decomposing due to the heat, as is the case with metal electrodes. Further savings are realized by the fact that the length of the tubes is reduced.

The colloidal graphite mentioned above, like various other materials suitable for the manufacture of the coating, has a high cathode drop as compared with pure metals. Any metal parts projecting from the surface of the layer which are in conductive connection with it, will cause the discharge to be concentrated at these metal parts. In such a case local heating will occur which will be strong enough to destroy the bulb at that spot, and which may even melt it.

It is therefore another feature of the present invention to prevent such occurrences. According to the invention, the lead-in wires, especially the cathode lead-in wires, are so disposed with respect to the conductive coatings that they are covered by the same. In other words, the cathode lead-in wires are disposed either within or underneath the surface of the conductive coatings.

This arrangement is illustrated in Fig. 2. Reference numeral 2a designates the glass bulb. The lead-in wires 5a and 6a which are connected to the conductive coatings forming the anode 1a and the cathode 3a, are so molten into the glass walls of the bulb 2a that the wires are arranged underneath the surface of the conductive coatings. The wires may extend slightly into the body of the coatings, without projecting, however, beyond their surfaces. In order to uniformly distribute the glow discharge, it is advisable to see that the distance between the two electrodes, at the points where the wires are led into the interior of the tube, is the same as at the other points. As stated above this arrangement of the lead-in wires is of advantage especially in cases where there is a high cathode

drop due to the properties of certain materials used. It has also been found advantageous to make a notch at the points where the wire is led through the wall (e. g. when the vessel is made of ceramic material), the notch serving to receive the lead-in wire so that no hardening of the electrode will occur in the interior of the tube.

Thorough investigation of the tubes described above has shown that the ignition voltage of these tubes is higher than that of discharge tubes of similar design in which electrodes made of metal sheet are used. This phenomenon is believed to be due to the fact that the materials used to form the coatings have gas producing properties, and consequently part of the gases of the gaseous mixture with which such tubes are filled combine with these newly formed gases. This factor is believed to be responsible for an increase in the ignition potential.

A further feature of the invention is to provide the tube with ignition electrodes which facilitate the starting of the tube in well known manner. Such ignition electrode is preferably made in a way similar to the main electrodes, i. e. in the form of a conductive coating disposed on the wall of the discharge vessel.

This feature is illustrated in Fig. 3 of the drawing. The glass bulb 2b is provided with a cathode layer 1b and an anode layer 3b. Lead-in wires 1b and 5b are connected to the anode and cathode layer, respectively. An additional coating 6b forming an ignition electrode is provided on the wall of the glass projection 4b. Electrode 6b, which is connected to the lead-in wire 3b, represents an auxiliary anode which during operation of the tube, is connected to the voltage source over a separate series resistor. This arrangement causes a relatively weak auxiliary current discharge between the main cathode 1b and the auxiliary anode 6b, producing ignition of the main discharge to the anode 3b at a very low ignition peak (difference between ignition and operating voltages).

The individual conductive coatings are preferably made in such manner that a protective layer, to be eliminated later, is applied on the insulating material at those places where no conductive coating is to appear. This protective layer is applied at the places desired, e. g. between the individual electrodes or at the sealing edge of the bulb. An excellent material for this protective layer is paraffin which has the favorable property that it will not be affected by the aqueous solutions which are used e. g. to apply the conductive electrode coatings. Instead of paraffin another easily liquefiable substance or an easily removable varnish may be used. It is also possible to use for the protective layer a material which is applied in the liquid state, and which can thereafter be taken off as a film or skin, such as for instance, collodion or gelatine. As soon as the protective skins are affixed, the conductive electrode coatings may be applied, which is preferably done in one manufacturing operation. During the coating, the protected places may be disregarded. As soon as the electrode coating has been applied, the protective layers are removed. The protective layers may, for example, be removed during the pumping step under suitable heating, the gasified substances being pumped out of the tube. It is possible, however, to dissolve the protective layers before the pumping, by applying suitable chemical substances.

The protective process described is suitable not only for the electrodes proper but for all parts going into the construction of the tubes and which are either to be covered, during their manufacture, with a conductive coating or are to be kept free therefrom.

According to another feature of the invention the discharge tubes intended for direct current operation are so constructed that, aside from the carbon cathode, the discharge space does not contain any other part operating as a cathode. This end can be attained either by manufacturing the lead-in wires from graphite or from graphite covered material, or by using other metallic leads covered by insulating material. Thus, the pressure in the interior of the discharge tube of any bare parts on a metallic lead-in having a lower cathode drop than carbon is avoided.

This feature is embodied in the constructions shown in Figs. 4 and 5. In Fig. 4, the lead-in wires consist of metal covered with an insulating material. In Fig. 5, on the other hand, the lead-in wires consist of graphite. Referring to Fig. 4, 2c is a glass bulb, to the interior wall of which two graphite coatings 1c and 3c are applied, of which 1c operates as the cathode, and 3c as the anode. The wire 1c is directly connected to the anode 3c, while the wire 3c is connected at 10c to the cathode 1c after passing through a tubular glass elongation 9c which forms part of the tube. The tubular elongation 9c, at its top, carries a disk 11c made of insulating material (e. g. mica), so that the wire is connected to the cathode at a point outside of the discharge space proper. In Figure 4 this space is marked 12c. Space 12c may be filled with an insulating substance e. g. glass wool, in order to prevent electric discharge therethrough.

In the embodiment shown in Fig. 5, 2d is the glass bulb, 1d represents the cathode layer, and 3d is the anode layer. The cathode lead-in 13d is made in the form of a conductive coating provided on the inside wall of the vessel 2d. In order to facilitate the manufacture, the form of the discharge vessel 2d is simpler than that shown in Fig. 4. As shown in Fig. 6, the anode 3d does not form a complete ring but is provided with a passage through which extends the lead-in 13d. Fig. 6 clearly shows that this form of construction is of special simplicity, because it merely consists of a substantially cylindrical glass bulb to the inside wall of which two conductive coatings are applied.

The present invention can also be used in the design of multi-chamber glow discharge potential dividers. In such a case, the tubes consist of a plurality of chambers, the walls of which are made of non-conductive material, for instance glass, ceramic material or the like. The electrode coating according to the invention is applied to the wall of the chambers. Tubes for high voltages can be manufactured by providing a suitable conductive connection of the chambers. The connecting points of two or more discharge gaps may be connected to a terminal contact for the purpose of deriving part voltages. It is advantageous to manufacture tubes of the type having a plurality of chambers even if no part voltages are to be derived, because in that case the discharge-voltage and the ignition potential respectively will be increased. The tubes may also be made of metal, using insulating separators. In such case the electrode material may be ap-

plied to the insulators, or, when special discharge properties are desired, to the metal wall.

What I claim, is:

1. A glow discharge tube for keeping voltages constant, comprising a double-walled container, the walls thereof being spaced apart, an anode and a cathode disposed in said container to form a glow discharge gap, and conducting means connected to said anode and cathode to admit electric current thereto, said anode and cathode having the form of layers, the latter consisting of colloidal graphite, the cathode layer being applied to the inner surface of the outer wall of said container, and the said anode layer being applied to the inner surface of the inner wall and a gas filling in said container in contact with said anode and cathode, whereby, upon admission of electric current, glow discharge takes place between the anode and cathode reducing the input voltage, while the out-put voltage remains substantially constant, independent of input current fluctuations.

2. A glow-discharge tube for keeping voltages constant comprising a double-walled container, the walls thereof being spaced apart, a first conductive layer provided on the inside surface of

5 the outer wall and a second conductive layer provided on the inside surface of the inner wall, and conductive means connected to said layers; said first layer forming the cathode and said second layer forming the anode of the glow discharge gap, and a third conductive layer, the latter being provided on the inside surface of said inner wall in spaced relation with respect to said second layer, a gas filling in said container in contact with said conductive layers, and conductive means connected to said third layer, the latter forming an ignition electrode.

10 15 3. Glow discharge tube in accordance with claim 1 in which the said layers consist of colloidal graphite, Aquadag, including an addition of metals of alkaline earths as activating media.

15 20 4. Glow type potential divider comprising a container, a gas filling therein, and a plurality of electrodes in said container, said electrodes forming a plurality of discharge gaps, said electrodes being in the form of layers and being applied to the interior walls of the container, said layers consisting of colloidal graphite.
